UNITED STATES PATENT OFFICE

153,974

DESIGN FOR A RUG SCRUBBING MACHINE

William L. Petersen, West New York, N. J., assignor to Clarke Sanding Machine Company, Muskegon, Mich., a corporation of Michigan

Application April 12, 1948, Serial No. 145,659

Term of patent 14 years

(Cl. D9—2)

To all whom it may concern:

Be it known that I, William L. Petersen, a citizen of the United States, residing at West New York, in the county of Hudson and State of New Jersey, have invented a new, original, and ornamental Design for a Rug Scrubbing Machine, of which the following is a specification, reference being had to the accompanying drawings, forming a part thereof.

In the drawings:

Figure 1 is a front elevational view of a rug scrubbing machine, showing my new design; and Figure 2 is a side elevational view thereof.

I claim:

The ornamental design for a rug scrubbing machine, substantially as shown.

WILLIAM L. PETERSEN.
